[57] CLAIM

The ornamental design for a programmable wedding clock with displays for years, months, days and hours of marriage, as shown and described.

DESCRIPTION

FIG. 1 is a front elevational view of the programmable wedding clock with displays for years, months, days and hours of marriage showing my new design;

FIG. 2 is a rear elevational view thereof;

FIG. 3 is a left view thereof;

FIG. 4 is a right view thereof;

FIG. 5 is a top plan view thereof;

FIG. 6 is a bottom plan view thereof;

FIG. 7 is an front isometric view thereof; and,

FIG. 8 is a rear isometric view thereof.

The broken line showing of numerals in FIGS. 1 and 7 is intended to represent the LCD in its non-operational setting.
